DOOR LOCK AND LATCH FOR CLOSURES

Sidney L. Neff, Salt Lake City, Utah

Application October 23, 1936, Serial No. 107,130

3 Claims. (Cl. 292—265)

My invention relates to closure operators, locks and articles of a like nature, and has for its object to provide a new and highly efficient garage or swinging door stop and lock.

5 A further object is to provide a sturdily constructed control device for garage doors which limits the amount of opening of the door to a predetermined amount, locks the door in the open position, until manually released and which 10 also locks the door closed when desired.

A still further object is to provide a simple 15 economically operated garage door lock which will hold the door open when desired, or which may be utilized to lock the door in the closed position and which device will be positive in its action and will not slip or loosen, due to wind or other causes shaking the door.

In the drawing

Figure 1 is a plan view of a section of the door 20 frame with the door shown in the locked open position.

Figure 2 is an enlarged view of a section of the top of the door and frame with my device shown holding the door locked in the closed position with parts of the door and bar cut away.

25 Figure 3 is a view of the door frame with my bracket attached thereto showing the bar in the locked position with the door removed.

Figure 4 is a plan view of the rod and bracket 30 in open position, parts cut away and other parts sectioned.

Figure 5 is a plan view of the locking bar.

Figure 6 is a perspective view of the support 35 and locking bracket.

Figure 7 is an end view of the eye part of the eye bolt shown in Fig. 4.

In the drawing I have shown the door as A, the frame as B, and the bracket for my device as C. The locking bar of my device is shown as D and is made of a hollow tube having one end flattened at 5 with a hole 6 transversely through the flattened end 5 through which an eye bolt 7 is passed forming a pivot for the end of the bar D. The threaded end 8 of the eye bolt is passed through the door A and secured thereto by a nut 9. The other end of the tube is cut on an angle at 10 and has a locking pin 11 passed through the tube near the angled end 10 said pin and end to drop into a channel in the support and locking bracket C. The bracket C is provided with a horizontal base 15 through which securing screws are inserted to secure the bracket to the frame cross piece 16 of the frame B. Integral with, and depending from this base 15 is a vertical plate 17 formed by bending the plate 15

at right angles and with the lower end of the plate 17 at right angles thereto and then back, parallel thereto, to form a channel 18 having the two sides thereof parallel and with the top edge of the inside edge 19 of the channel spaced from 5 the base 15 as shown at 20 in the drawing, Figures 4 and 7.

Through the vertical plate 17 which forms one side of the channel 18 of the bracket C, I provide an opening or slot 21 through which opening the 10 locking and control bar D of my device is carried and operated. A notch 24 is cut in the bottom side of the bar D near the flattened end 5 to provide a locking notch in which the edge 19 may fit when it is desired to use the device to lock the 15 door in the closed position where the device is being used on a door in a garage or building having another separate entrance thereinto.

The operation of my device is as follows:

The bracket C is mounted by suitable screws or 20 bolts onto the under side of the cross piece 16 of the door frame B and the eye bolt is secured through the door. The bar is passed through the opening or slot 21 in the bracket and is then ready for use. When opening the door, the end 25 of the bar will drop by gravity into the channel 18 of the bracket with the angled end 10 of the bar fitting against the upturned side 19 locking the door open with the locking and limiting pin 11 engaging the side 17 of the channel wedging 30 the end of the bar D in the channel 18 and in the slot 21. When in this position no movement of the door can dislodge the pin 11 and beveled or angled end 10 from the channel 18.

When it is desired to close the door, the bar is 35 elevated, lifting the end 10 and pin 11 from the channel 18, and the door may then be closed, the bar sliding along the top edge of the side 19 and when the bracket is set to lock the door closed, the notch 24 comes into use. When the door is so closed, the weight of the bar D will cause it to engage the notch 24 with the edge 19 of the bracket, thereby locking the door closed until such time as the bar is again manually elevated for opening the door. When it is not 40 desired to lock the door from within, the bracket C may be set so far from the door when in the closed position, that the notch 24 will not come into contact with the channel edge 19 and therefore the conventional method of locking the door 45 may be employed.

Having thus described my invention I desire to 50 secure by Letters Patent and claim:

1. In a door lock and catch of the class described the combination of a bracket having a 55

depending channel along one edge thereof and a vertical slot through the depending edge; a sliding bar carried through said slot having one end pivotally secured to the garage door and the other end cut on a slant and adapted to drop down into said channel when the door is opened; and a pin passed through said sliding bar near the slanting cut end to limit the outward movement of the door, and aid in locking the slanting end in the channel.

2. In a door lock of the class described, the combination of a bracket formed with a base plate for attachment to a door frame in a horizontal plane; a flange extending from said base plate and having its end formed into a channel the outer lip of said channel being spaced from said base, said flange having an opening therethrough; a locking bar carried in said opening with one end secured pivotally to the door and the other end slidably carried in said opening and having the end cut away on a bevel to fit against the inner edge of said channel when the door is opened; and a limiting pin driven through

said bar near the end adapted to limit the movement of said bar through said opening.

3. In a garage door lock and catch, the combination of a bracket formed with the top to fit along the door frame on a horizontal plane and having a depending channel formed parallel to said top with a slot through the vertical depending portion thereof; a sliding bar carried through said slot, said bar having one end pivotally secured to the garage door and the other end cut on an angle substantially equal to the engaging angle of the bar to the bracket when the door is in the full open position; a notch cut in said bar near the pivoted end said notch and bar to drop down over the vertical end of the channel of said bracket when in the full closed position to lock the door closed; and a cross pin passed through said sliding bar near the free end thereof said pin being on an angle to said bar parallel to the slanting end thereof with the end of the bar and pin to drop down into said channel when the door has been fully opened to lock the door open.
